US00D564539S

(12) United States Design Patent (10) Patent No.: US D564,539 S
(45) Date of Patent: * Mar. 18, 2008

(54) USER INTERFACE FOR A PORTION OF A DISPLAY SCREEN

(75) Inventor: Niels Van Dongen, Seattle, WA (US)

(73) Assignee: Microsoft Corporation, Redmond, WA (US)

() Term: 14 Years

(21) Appl. No.: 29/249,891

(22) Filed: Oct. 25, 2006

(51) LOC (8) Cl. 14-04

(52) U.S. Cl. D14/487

(58) Field of Classification Search D14/485-495; 715/700-867, 973-977

See application file for complete search history.

(57) CLAIM

The ornamental design for a user interface for a portion of a display screen, as shown and described.

DESCRIPTION

The FIGURE is a front view of a user interface for a portion of a display screen showing my new design.

The broken line showing of a device embodying the display screen is for illustrative purposes only and forms no part of the claimed design.

1 Claim, 1 Drawing Sheet
